(57) CLAIM

I claim the ornamental design for a boat hull with splash guard, as shown and described.

DESCRIPTION

FIG. 1 is a front perspective view of a boat hull with splash guard showing my new design according to my invention;

FIG. 2 is a top plan view thereof;

FIG. 3 is a bottom plan view thereof;

FIG. 4 is a right side elevational view thereof, the left side elevational view being the mirror image thereof;

FIG. 5 is a rear elevational view thereof; and,

FIG. 6 is a front elevational view thereof.
